(57) **CLAIM**

The ornamental design for the adjustable wrench, as shown and described.

DESCRIPTION

FIG. 1 is a perspective view of an adjustable wrench in accordance with the present invention;

FIG. 2 is a front view of the adjustable wrench of FIG. 1;

FIG. 3 is a rear view of the adjustable wrench of FIG. 1;

FIG. 4 is a left side view of the adjustable wrench of FIG. 1;

FIG. 5 is a right side view of the adjustable wrench of FIG. 1;

FIG. 6 is a bottom view of the adjustable wrench of FIG. 1;

FIG. 7 is a top view of the adjustable wrench of FIG. 1.

The dash-dash broken lines are for the purpose of illustrating portions of the adjustable wrench and form no part of the claimed design. The dot-dash broken lines define the bounds of the claimed design and form no part thereof.
